APPARATUS FOR INVESTING DENTAL
CASTING PATTERNS

David W. Phillips, Chicago, Ill.

Application March 3, 1932, Serial No. 596,447

7 Claims. (Cl. 22—97)

This invention relates to apparatus for making dental castings, and particularly to improved means for investing a casting pattern in a body of investment.

5 An important object of the invention is to provide means for effecting absorption of water from the body of investment to produce quick initial setting of the latter after the pattern has become embedded therein, thereby materially reducing the time required to prepare the finished casting.

Other objects and advantages of the invention will be apparent from the following detailed description, which, taken in connection with the 15 accompanying drawing, discloses a preferred embodiment thereof.

Referring to the drawing:

Fig. 1 is a top plan view of an investment container and a sprue holder constructed in accordance with the invention;

Fig. 2 is a broken vertical section through the improved container and holder assembly, the view being taken as indicated by line 2—2 of Fig. 1;

Fig. 3 is a perspective view of the metal rim portion of the sprue holder which is adapted to receive an absorbent refill element;

Fig. 4 is a bottom plan view of the sprue-supporting refill element adapted to be removably secured within the metal rim piece shown in Fig. 3; and

Fig. 5 is a detail section of a modified form of absorbent sprue-supporting element.

Briefly, the invention consists in making the sprue holder of a material which is capable of 35 quickly absorbing water from the mass of moist investment when it is brought into contact with the latter. This rapid removal of water from the investment reduces the time required for the setting of the mass, and thereby speeds up the 40 investing operation. Also the rapid absorption of water from the investment after the pattern has become imbedded therein tends to produce smoother castings, for the reason that it tends to provide a drier, denser investment about all 45 surfaces of the pattern, thereby eliminating excessive moisture which tends to cause surface imperfections in the finished casting. Although the sprue holder may be formed entirely of an absorbent material, I prefer to construct it in

50 two parts, one part consisting of a metal rim piece which is received on the container, and the other part, which carries the pattern, consisting of an absorbent refill element, which is removably secured within the rim piece.

55 Referring to the drawing, the numeral 8 designates a tubular container for receiving a body or mass of investment 9. The lower end of the container 8 is closed by a rubber end cap 11, the marginal rim portion of which is turned upwardly, as indicated at 12, to form a water-tight seal with the side walls of the container. The use of the rubber end cap for closing one end of the container is particularly desirable in water-bath technique, since it prevents seepage of water into the body of investment when the 65 container is immersed. Because of its elasticity, the cap 11 will yield under pressure of the expanding investment to permit full setting expansion of the latter and at the same time it will maintain a water-tight seal with the end of 70 the container. The use of the rubber end cap is also desirable, for the reason that it may be readily snapped around the ends of containers of various sizes and shapes.

The sprue holder illustrated in Figs. 1—4 comprises a rim piece 13, and an absorbent sprue supporting refill element 14. Rim piece 13, which is preferably made of metal, serves as a means for supporting element 14 in proper position relative to the investment container. Said rim piece 13 comprises: a central body portion 15, which is tapered inwardly to engage the sides of the cone-shaped element 14; and a top flange piece 16, which is formed as an integral part of body portion 15, and which is adapted to rest on the top edge of container 8 when the holder is positioned thereon, as shown in Fig. 2. Refill element 14, as previously noted, is cone-shaped so that when it is positioned on the investment container it will project into the mass of investment to form, when removed therefrom, a corresponding cone-shaped cavity in the body of investment, said cavity serving as a crucible for receiving molten metal in the subsequent casting operation. A sprue 17, which supports a pattern 18 in the investment, is removably anchored in element 14 by means of a body of wax 19 which serves to anchor the upper end of the sprue in an axially disposed cavity formed in element 14.

Element 14 is removably secured in rim piece 13 by means of tongue members 21 which project inwardly from flange 16 of said rim piece, said tongue members being received in notches 22 formed in the top edge portions of element 14, 105 said notches being spaced to correspond to the spacing of tongue members 21. As will be noted from Figs. 3 and 4, tongue members 21 are pitched downwardly, and the rim portions of refill element 14 adjoining notches 22 are bevelled as in

100

105

110

- dicated at 23. It will be evident that when element 14 is positioned on rim piece 13, with notches 22 disposed opposite tongue members 21, it may be dropped into position, whereupon a turning of 5 said element in a counter-clockwise direction relative to rim piece 13, viewing Fig. 1, will cause tongue members 21 to wedge upon bevelled surfaces 23 thereby securely anchoring element 14 in position in rim piece 13.
- 10 Refill element 14 is made of a water-absorbent material, so that when placed on the investment container it will extract water from the body of investment to produce quick setting of the mass. Various materials may be used for forming element 14. Among the materials which are suitable for use for this purpose, there may be mentioned set plaster of Paris, set hydrocal, and various pressed fibrous materials such as absorbent paper, absorbent cloth, and the like.
- 15 The manner of use of the absorbent sprue-supporting refill element will be apparent from Fig. 2. After the investment has been prepared it is placed in container 8, the lower end of which has previously been closed by rubber end cap 11. A 20 double layer of moistened asbestos paper 24 is inserted as a lining for the walls of the investment container in accordance with the usual practice. Refill element 14 is then secured in place in rim 13, after which wax pattern 18 is placed on sprue 25 17 and the latter is anchored in position in element 14. The entire sprue supporting assembly is then lowered onto the investment container until flange 16 engages the upper edge of container 8. The refill element 14, being absorbent in character, rapidly extracts water from the body of investment, thereby bringing about an almost immediate initial setting of the entire mass of investment. The time required for the investing operation is thus materially reduced. Also by 30 reason of absorption of water by element 14, there is obtained a drier, denser investment about the surfaces of the pattern which enables the production of smoother castings. The greater the proportion of water present in a mix of inlay investment, the rougher will be the surfaces of the finished casting. This is due to the fact that a large 35 proportion of water in the mix tends to cause roughness in the surfaces of the set mass of investment after the water and wax have been burned out of the set investment. On the other hand, an almost immediate set of the investment prevents roughness in castings caused by any slight vibration of the mass of investment in the container before it sets. For example, slight vibration caused by a lathe running on the work 40 bench will cause water to separate in the investment near the pattern surfaces before setting occurs. Upon burning out of the wax, this water is removed and the unevenness thus produced in the investment surfaces causes a corresponding 45 roughness in the surfaces of the finished castings.
- 50 After final setting of the investment, the sprue holder is removed from the container, this being effected by imparting a twisting movement to rim 13 which effects separation of rim 13 and element 14 from the set mass of investment. The body of wax 19, which holds sprue 17 in element 14, yields during this twisting operation to allow separation of the sprue from the holder. The 55 tongue members 21 should be so related to the surfaces 23 of element 14 that when the holder is twisted from engagement with the container, these tongue members will wedge more tightly onto the surfaces 23 to prevent element 14 from becoming loosened in rim 13. In order to prevent 60
- turning of the set body of investment in container 8 during removal of the sprue holder, I make the upper end of said container hexagonal in shape, as shown in Figs. 1 and 2. The hexagon-shaped portion need extend over but a small portion of the length of container 8 and is formed as a continuation of the cylindrical side walls, the joining of these portions being indicated by line 25 in Fig. 2.
- 65 If desired, the sprue holder may be made of a single piece of absorbent material, as indicated in Fig. 5. In this form the holder, which is indicated generally by the numeral 26, includes a main cone-shaped body portion 27 and a peripheral rim portion 28, the latter serving as a support for the holder when it is placed on the top of container 8. The complete unit is made of an absorbent material of the type hereinbefore specified. The sprue 29 is removably secured in the body portion of the holder by means of a mass of wax 31 in the same manner as described for the form shown in Figs. 1-4.
- 70 When using the form of holder shown in Fig. 5, some difficulty may be encountered in placing the holder on the container, due to the fact that water 100 may be so quickly absorbed from the portions of investment near the upper edge portions of the ring that the mass becomes somewhat dry and does not allow the holder to be freely pushed into place. By the use of rim piece 13 this difficulty 105 is avoided, since water is not rapidly absorbed from the portion of the investment lying near the upper edge of the container, so that these portions remain somewhat moist and allow the holder to be easily placed in position on the container.
- 75 In Fig. 2 I have shown the use of an absorbent disc 32 which is interposed between end cap 11 and the body of investment 9. This disc is intended to fit loosely within container 8, being held 110 in place by end cap 11. It may be made of any one of the absorbent materials hereinbefore specified, and affords additional means for effecting rapid extraction of water from the mass of investment to reduce the setting time. The disc 32 115 may be used in conjunction with the absorbent sprue holder shown in Fig. 2, or may be used in conjunction with the regular all-metal sprue supporter. While the bulk of the water absorption takes place through the absorbent sprue 120 holder, because of its greater mass, the absorbing action of disc 32 is appreciable and its use tends to further reduce the time required for effecting initial setting of the investment.
- 80 The foregoing detailed description has been 125 given for clearness of understanding only, and no unnecessary limitations should be understood therefrom, but the appended claims should be construed as broadly as permissible in view of the prior art.
- 85 What I regard as new and desire to secure by Letters Patent is:
1. In an apparatus for investing dental casting patterns, including an investment container, a pattern-supporting sprue, and a holder therefor 130 adapted to be placed upon one end of the container, a closure for the other end of the container, comprising a flexible cap adapted to fit upon the lower end of the container and having an annular flange adapted to grip the container 135 wall, said cap providing a water-tight closure and being extensible under pressure of the investment against said cap.
2. Apparatus for investing a casting pattern comprising a tubular container for holding a mass 140

of investment, a pattern-supporting sprue, a crucible-forming holder for said sprue adapted to be placed on one end of said container, said holder being formed of a material capable of absorbing water from the investment to thereby produce quick initial setting of the mass after the pattern has become embedded therein, and means affording a closure for the other end of the container, said last-mentioned means including a body of absorbent material for removing water from the investment to further aid in reducing the setting time of the mass.

3. Apparatus for investing a casting pattern comprising in combination with an investment container, a pattern-forming sprue, and a holder therefor adapted to be placed upon one end of the container, a removable cap for the other end of the container, and a layer of absorbent material positioned in said cap and adapted to contact with the body of the investment when the cap is in place on the container.

4. Apparatus for investing a casting pattern comprising an investment container open at one end, the other end thereof being closed by a removable cap forming a water-tight seal with the body of the container, said cap being formed of an elastic material adapted to yield under pressure of the expanding investment, a pattern-supporting sprue, a crucible-forming holder for said sprue adapted to be placed on the open end of the container, said holder being formed of a material capable of absorbing water from the investment to thereby produce quick initial setting of the mass after the pattern has become embedded therein, and a layer of absorbent material interposed between said end cap and the adjacent body of investment, said absorbent layer serving to remove water from the investment to further aid in reducing the setting time of the mass.

40 5. Apparatus for investing a casting pattern comprising an investment container open at one end, the other end thereof being closed by a re-

movable cap forming a water-tight seal with the body of the container, said cap being formed of an elastic material adapted to yield under pressure of the expanding investment, a pattern-supporting sprue, a crucible-forming holder for said sprue adapted to be placed on the open end of the container, said holder comprising a rim piece for engaging the end of the container, and a sprue-supporting refill element removably secured within said rim piece, said supporting element being formed of a material capable of absorbing water from the investment to thereby produce quick initial setting of the mass after the pattern has become embedded therein, and a layer of absorbent material interposed between said end cap and the adjacent body of investment, said absorbent layer serving to remove water from the investment to further aid in reducing the setting time of the mass.

6. In an apparatus for investing dental casting patterns, including an investment container, a crucible-former arrangeable upon an end of the investment container and adapted to be pressed against the body of the investment contained therein, the portion of said crucible-former which contacts said investment being formed of water-absorbent material capable of extracting water from a mix of investment within the container to thereby produce quick setting of the investment and the production of smooth castings.

7. In an apparatus for investing dental casting patterns, including an investment container, a crucible-former arrangeable upon an end of the investment container, said crucible-former comprising a rim piece for engaging the end of the container, and a sprue-supporting refill element removably secured within said rim piece, said element being formed of an absorbent material capable of extracting water from a mix of the investment within the container.
